UNITED STATES PATENT OFFICE.

LESLIE WAGGENER LOVING, OF PARIS, TENNESSEE.

BUGGY-TOP SUPPORT.

No. 838,632.

Specification of Letters Patent.

Patented Dec. 18, 1906.

Application filed January 8, 1906. Serial No. 295,059.

To all whom it may concern:

Be it known that I, LESLIE WAGGENER LOVING, a citizen of the United States, residing at Paris, in the county of Henry and State of Tennessee, have invented certain new and useful Improvements in Buggy-Top Supports; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to buggy-top supports, and has for its object to provide a device of this class which is simple in its construction, easy to attach, strong, durable, and efficient.

20 With this object in view my invention consists in the novel construction for attaching the prop or support to the rubber-iron of the buggy.

25 Referring to the accompanying drawings, Figure 1 is an elevation of the top-prop in position on buggy. Fig. 2 is a perspective view of prop. Fig. 3 is a vertical transverse section through rubber-iron and securing parts of prop. Fig. 4 is an elevation of the 30 double yokes; and Fig. 5 is a vertical transverse section through rubber-iron and inner yoke, showing position of yoke when placed on rubber-iron.

35 Like numerals of reference indicate the same parts throughout the several figures, in which—

40 1 indicates the buggy-body; 2, the top; 3, the lower buggy-bow; 4, the rubber-iron, and 5 the top prop or support. The top prop or support 5 comprises a spring 6, coiled as shown, the free end 7 of which carries a suitable bow-rest 8.

45 9 indicates the inner yoke, 10 the outer yoke, and 11 the securing-bolt, said outer yoke 10 being provided with bolt-holes 12, and the inner end 13 of the spring 6 being provided with a bolt-hole 14, said bolt-holes in the yoke 10 and bolt-hole in the spring 6 registering, as shown in Fig. 3.

50 Having thus described the several parts of my invention, its operation is as follows: The rubber-irons 4 on buggies of different manufacture are of different sizes, and therefore to make a buggy-top prop commercially practical it is essential that they can be attached to

buggies of any manufacture without altering the prop or support. In my construction the inner yoke 9 is constructed so as to straddle the rubber-iron 4, as shown in Fig. 5, the ends of the yoke being spread, as shown, so as to accommodate the largest rubber-irons. The outer yoke 10 is then passed over the inner yoke 9, the spring 6 is placed in position, and the bolt 11 is passed through the bolt-holes 12 and 14, and the top is threaded on the bolt. As shown in Fig. 4, the inner yoke 9 is considerably longer than the outer yoke 10, which permits of a wide range of adjustment of the outer yoke 10 and spring 6, as shown in dotted lines in Fig. 4, in order to have the bow-rest 8 directly under the bow 3. When this adjustment has been made, the bolt-top is threaded down hard, which draws the two yokes 9 and 10 into position shown in Fig. 3, causing the inner yoke 9 to tightly engage the rubber-iron and drawing the spring 6 firmly against the outside of the outer yoke 10 in such manner that all the parts will be rigidly drawn together and rattle or movement absolutely prevented. As is obvious, the prop or support can be readily removed and attached to another buggy, while should any breakage occur the broken part can be replaced without wasting the other parts.

Having thus fully described my invention, I do not wish to be understood as limiting myself to the exact construction herein set forth, as various slight changes may be made therein which would fall within the limit and scope of my invention; and I consider myself clearly entitled to all such changes and modifications as would fall within the compass of the following claims.

What I claim as my invention, and desire to secure by Letters Patent of the United States, is—

1. In a buggy-top prop or support, the combination of a spring constructed to support the buggy-top, an inner yoke arranged to be passed over the rubber-iron of the buggy, an outer yoke arranged to be passed over said inner yoke, and means passing through said outer yoke and engaging said spring for securing the parts firmly in position on said rubber-iron, substantially as described.

2. In a buggy-top prop or support, the combination of a spring constructed to support the buggy-top, an inner yoke arranged

to be passed over the rubber-iron of the buggy, an outer yoke arranged to be passed over said inner yoke, said inner yoke being longer than said outer yoke to permit adjustment of said outer yoke on said inner yoke, and means for securing the said spring to the said outer yoke to securely bind the parts together in such manner that rattling and

movement thereof are obviated, substantially as described.

In testimony whereof I affix my signature in presence of two witnesses.

LESLIE WAGGENER LOVING.
